UNITED STATES PATENT OFFICE.

CHARLES F. KOLB, OF CHICAGO, ILLINOIS.

HAME-FASTENER.

No. 920,878.

Specification of Letters Patent.

Patented May 4, 1909.

Application filed June 3, 1908. Serial No. 436,479.

To all whom it may concern:

Be it known that I, CHARLES F. KOLB, a citizen of the United States, residing at Chicago, in the county of Cook and State of Illinois, have invented certain new and useful Improvements in Hame-Fasteners; and I do hereby declare the following to be a full, clear, and exact description of the invention, such as will enable others skilled in the art 10 to which it appertains to make and use the same.

This invention relates to hame fasteners, and especially to that class of hame fasteners dispensing with buckles and straps.

15 An object of the invention is to provide a hame fastener cheaply and economically made and which will secure the separable ends of hames together with a considerable degree of tension and one which is easily and 20 quickly applied and removed, and which will remain in locked position when applied.

A further object of the invention is to provide in a hame fastener a tubular member which is applied to the extremity of one 25 hame with a member applied to the extremity of the co-acting hame adapted to be slidably inserted in the tubular member and with lever adjustment for drawing the members together and locking them under 30 tension.

With these and other objects in view, the invention comprises certain novel constructions, combinations and arrangements of parts, as will be hereinafter fully described 35 and claimed.

In the drawings:—Figure 1 is a fragmentary view of a collar and hames with the improved fastening member in operative position thereon. Fig. 2 is a view with the tubular member in longitudinal section and the co-acting member in side elevation showing other parts broken away. Fig. 3 is a view of the tubular member in inverted plan with the locking lever in locked position. Fig. 4 is a 40 view in inverted plan of a tubular member stamped from sheet material. Fig. 5 is a view in end elevation of the tubular member shown at and taken on line 5 of Fig. 4. Fig. 6 is a view in end elevation of the co-acting member adapted for use in association with the sheet metal tubular member. 45

Like characters of reference designate corresponding parts throughout the several views.

50 The improved hame fastener forming the subject-matter of this application comprises

two sections, one of which 10 is tubular in form and is either cast as indicated at Fig. 2 or is composed of sheet material stamped and bent as shown at Fig. 4. Upon either 60 form of tubular member so employed ears 11 are provided and therein or therebetween is pivoted a lever 12 as by the pivot 13. Intermediate the ends of the lever 12 a stirrup 14 is pivoted as by the pintle 15 and at the 65 end opposite the lever 12 is provided with a cross pin 16. The member 10 is also provided at one end with a hook 17 positioned and proportioned to engage the loop or eye 18 upon the end of a hame 19. For co-action 70 within the member 10 a member 20 is provided having a hook 21 similar to the hook 17 at the member 10 and similarly adapted to engage the loop or eye 22 of the hame 23. Along the body of the member 20 is a plurality of spaced teeth or abutments 24 forming therebetween recesses for engaging the cross pin 16. When the sheet metal tubular member is employed the co-acting member is 75 preferably formed as shown in end elevation 80 at Fig. 6 being also formed of sheet metal stamped as shown at 25 and with upturned lever ribs 26 spaced to move longitudinally between the spaced edges 27 of the tubular member 10. 85

In operation the member 10 and the member 20 are, of course, respectively engaged upon the hames 19 and 23 and when such hames are to be connected the extremity of the member 20 is inserted in the extremity 90 of the tubular member 10 and the lever 12 moved to the position shown at Fig. 2 and the cross pin 16 engaged upon one of the teeth 24. The lever 12 is then moved upon its pivot 13 as indicated by the arrow to the 95 position shown in Fig. 1 whereupon a straight line connecting the pivot pins 15 and 16 passes between the pivot 13 and the tubular member so that the strain of the hames 10 tends to hold the lever 12 in locked position against the tubular member 10. When the hames are to be removed the end 100 of the lever 12 is forcibly moved in reverse direction from that indicated by the arrow which relieves tension upon the member 20 105 and the cross pin 16 may then be easily moved from engagement with the tooth 24 and the members separated.

What I claim as new and desire to secure by Letters Patent is:

1. In a hame fastener, a tubular member provided with a hooked extremity, a mem-

ber adapted to slide within the hooked member and provided at one end with a hook and along the surface with a plurality of spaced teeth, spaced ears upstanding from the tubular member, a lever pivoted between the spaced ears, and a bail pivoted upon the lever and provided with a cross bar adapted to engage the spaced teeth of the inner member.

5 10 2. A hame fastener comprising a curved tubular member, provided at one end with a hook, spaced ears upstanding from the convex side of the curved tubular member, a curved member adapted to slidably enter the tubular member, a hook formed upon one end

of the latter curved member, spaced teeth formed upon the convex side of the inner slideable member, a lever pivoted between the upstanding ears, and a bail pivoted to the lever having a cross head adapted to engage the spaced teeth and so proportioned that a line drawn between its pivot and cross head passes the pivot point of the lever both in opening and closing.

20 In testimony whereof I affix my signature 25 in presence of two witnesses.

CHARLES F. KOLB.
